CLAIM

The ornamental design for a tissue paper holder, as shown and described.

DESCRIPTION

FIG. 1 is a perspective view of a tissue paper holder, showing my new design;

FIG. 2 is a side-elevational view of the side not seen in FIG. 1;

FIG. 3 is a cross-sectional view taken substantially along line 3—3 of FIG. 5;

FIG. 4 is a bottom-plan view thereof; and

FIG. 5 is a top-plan view thereof.

FIG. 1

FIG. 2

FIG. 3

FIG. 4

FIG. 5
